MINE JACK

Otto Sann, Johnstown, Pa.

Application August 7, 1931. Serial No. 555,812

5 Claims. (Cl. 254—104)

This invention relates to improvements in mine jacks and aims to provide a simple and durable device of this character which can be ruggedly constructed and manufactured inexpensively.

5 One object of the invention is to provide a mine jack of a minimum number of parts. This is desirable because the tool is handled by relatively unskilled labor, not particularly trained in assembling coacting parts of mechanical devices. Moreover, frequently with the types of jacks heretofore employed having many elements, some of the parts are easily lost or misplaced, in which case the device is either practically inoperative or substitute parts of a makeshift character are substituted to less effectively take the place of lost parts. This is a dangerous procedure where the jack is used to shore up or support the roof of a mine or other heavy mass. Failure of the parts is apt to result in loss 20 of life or damage to machinery used in mining operations.

My improved jack consists solely of two main coacting parts of rugged construction which are parted on an inclined plane, one part being 25 adapted to ride upon wedge-like faces of the other and the device having a locking latch for releasably holding the two parts in supporting position.

One embodiment of the invention is illustrated 30 in the accompanying drawing wherein;

Fig. 1 is a side elevation of the jack in working position with a portion broken away;

Fig. 2 is a central longitudinal section through the jack showing the complementary parts in released position;

Fig. 3 is a detailed elevation of a portion of the jack viewed from the right side of Fig. 1;

Fig. 4 is a horizontal section on line 4—4 of Fig. 1.

40 Referring in detail to the drawing, the improved jack consists of two complementary sections 10 and 12 having respective base and head portions 14 and 16 formed integral with the hollow column sections 18 and 20. Strengthening ribs 22 and 24 merge from the base 14, and cap 16, respectively, into the column sections, as shown.

The complementary members 10 and 12 are 50 parted on a diagonal or oblique plane, as indicated in Figs. 1 and 2, at 26. To prevent the parts from turning relatively to one another and also to properly align them for proper interengagement, the member 10 is provided with upwardly extending ribs or projections 28—28 which slidably engage

similarly shaped grooves 30—30 formed in the member 12.

A latch member 32 is loosely pivoted on a stud 34 which is supported in suitable bearing lugs 36 extending inwardly from the interior of the member 12. The latch is formed with a tooth 38 which, when the jack is in its locked position, engages the inclined face 40 of an abutment 42 extending inwardly from the member 10.

An opening 44 is formed in the member 12 of the jack and the tail 48 of the latch extends through this opening. The height of the slot 44 is such that its upper and lower edges, respectively, 50 and 52 serve as stops to limit the rocking movement of the latch. When in working position, the tail of the latch strikes the shoulder 52 and the tooth 38 is thus accurately positioned for engagement with the abutment 42. In order to release the latch so as to separate the complementary parts of the jack, the tail 48 is struck from below 75 by means of a sledge or other tool, thus turning the latch to the position of Fig. 2, the angular movement of the latch being limited at this time by the tail striking the upper surface 50 of the slot. If desired, the members 10 and 12 may be 80 provided with suitable handles such as indicated at 54 and 56. These may be formed of ordinary bar stock cast in place or alternately they may be cast integrally.

It will be readily understood that in order to engage the jack with a roof or other overhead device to be supported, the member 10 will be placed in the desired position, then the member 12 will be engaged therewith, the slots 30 thereof being positioned for coaction with the ribs 28. The part 12 is then pushed along the inclined surface 26, a sledge hammer or other tool being used if required. Upon reaching the position of Fig. 1, the latch will drop into locked position by gravity and the jack is then in its normal operative position. To 95 release the parts, it is merely necessary to strike the latch from below and then tap the upper part with a sledge hammer so as to cause it to ride down the incline 26, whereupon the jack can be moved to another desired working position. 100

The improved device, as above described, is extremely simple in construction and operation, it contains no parts which are apt to be lost or misplaced and it is practically foolproof in operation.

Various changes in arrangement and substitution of equivalents may be made by those skilled in the art without departing from the invention as defined in the appended claims.

What I claim is:—

1. A mine jack comprising two complementary 110

and hollow post members having respective base and cap portions and parted in a plane inclined with respect to said base and cap portions, a latch pivotally mounted interiorly in one of said members and having a portion thereof adapted for engagement with an internal abutment on the other member.

2. A mine jack consisting solely of two hollow post members having coacting inclined portions, and a releasably movable latch internally disposed in one of the members having a portion for engagement with an internally disposed abutment on the other member and means for limiting the movement of said latch member.

3. A mine jack comprising two hollow post members parted on a plane inclined with respect to the longitudinal axis of said members, a projection disposed upon the inclined section on one member and a coacting groove recessed in the inclined section of the other member, an internally disposed pivoted latch carried by one member, an internally disposed abutment for cooperation therewith carried by the other member, and means limiting the pivotal movement of said latch.

4. A mine jack comprising a lower hollow post member having a substantially horizontal base, an upper hollow post member having a substantially horizontal cap, the upper part of the lower

member and the lower part of the upper member having coacting portions inclined with respect to said base and cap portions, an abutment formed in the inclined section of the lower member, an internally disposed latch pivoted to the upper member and having a tooth for coaction with said abutment, said latch having a tail and said upper member having a slot through which the tail projects, the length of the slot being proportioned to limit movement of said latch.

5. A mine jack of the character described comprising a lower hollow post member having a substantially horizontal base, an upper hollow post member having a substantially horizontal cap, the upper part of the lower member and the lower part of the upper member having coacting portions inclined with respect to said base and cap portions, a projection disposed upon the inclined plane section of one member and a coacting groove recessed in the inclined section of the other member, an abutment formed in the inclined section of the lower member, an internally disposed latch pivoted to the upper member and having a tooth for coaction with said abutment, said latch having a tail and said upper member having a slot through which the tail projects, the length of the slot being proportioned to limit movement of said latch.
